ATTORNEY

WITNESS:

UNITED STATES PATENT OFFICE.

ROBERT B. TYSON, OF LONGVIEW, TEXAS, ASSIGNOR, BY DIRECT AND MESNE ASSIGNMENTS, OF THIRTY-NINE PER CENT TO RUTH CARROLL BERRY, OF SHREVEPORT, LOUISIANA, AND TWENTY PER CENT TO LEWELL C. BUTLER, OF SHREVEPORT, LOUISIANA.

GAS BURNER.

Application filed November 4, 1927. Serial No. 231,122.

This invention relates to a gas burner, the general object of the invention being to provide means for securing the maximum amount of heat with the minimum amount of fuel by 5 providing means whereby gas and air are thoroughly mixed together and then passed through a nozzle or opening to the point of combustion.

This invention also consists in certain 10 other features of construction and in the combination and arrangement of the several parts, to be hereinafter fully described, illustrated in the accompanying drawings and specifically pointed out in the appended claim.

15 In describing my invention in detail, reference will be had to the accompanying drawings wherein like characters denote like or corresponding parts throughout the several views, and in which:—

20 Figure 1 is a perspective view of the improved burner.

Figure 2 is a longitudinal sectional view thereof.

As shown in these views, the burner comprises a hollow part 1 and a nozzle part 2 which are connected together by the curved pieces 3, the entire device being preferably formed integral. The outer end of the part 1 is tapped, as at 4, so as to receive a pipe which 25 is connected with a source of gas supply. A small screw threaded opening is made in the front end of the member 1 to receive a tip 5 which projects into the space formed by the ends of the members 1 and 2 and the members 3. The part 2 has an opening 6 extending 30 entirely through it, the axis of which is in alignment with the axis of the tip.

As shown in Figures 1 and 2, the members 3 are made much narrower than the members 40 1 and 2 and they connect the central portions

of the parts 1 and 2 together. Thus air can enter the space between the two members 1 and 2 from below and from above and this air will be thoroughly mixed with the gas escaping from the tip 5 and this mixture will travel 45 through the opening 6 under the propelling action of the gas leaving said tip. Thus as the mixture leaves the part 2, it will be in a highly inflammable state. The device can be used with natural gas or artificial gas. 50

It is thought from the foregoing description that the advantages and novel features of my invention will be readily apparent.

I desire it to be understood that I may make 55 changes in the construction and in the combination and arrangement of the several parts, provided that such changes fall within the scope of the appended claim.

What I claim is:—

A burner of the class described comprising a 60 front member having a bore extending entirely through the same, a rear member having a chamber therein, a pair of curved side pieces connecting the adjacent ends of the two members together, said side pieces being of less 65 width than the width of the members, the front end of the rear member having a threaded hole therein, a nozzle threaded in said hole and extending into the space formed by the adjacent ends of the two members and by 70 the side pieces, the rear end of the rear member having a threaded hole therein to receive a supply pipe, the rear end of the front member and the front end of the rear member 75 having beveled upper and lower parts leaving straight central parts to which the side members are connected.

In testimony whereof I affix my signature.

ROBERT B. TYSON.
